UNITED STATES PATENT OFFICE.

GEORGE FRANK PRICE, OF HEGEWISCH, ILLINOIS.

BRACKET-HOLDER.

SPECIFICATION forming part of Letters Patent No. 734,948, dated July 28, 1903.

Application filed June 21, 1902. Serial No. 112,720. (No model.)

To all whom it may concern:

Be it known that I, GEORGE FRANK PRICE, a citizen of the United States, residing at Hegewisch, in the county of Cook and State of Illinois, have invented new and useful Improvements in Shade-Fixtures, of which the following is a specification.

This invention relates to shade-fixtures, and has for its object the production of a device of this character wherein the bracket proper is capable of adjustment to compensate for shade-rollers of varying length, and, further, to provide new and improved means for locking the bracket in its adjusted position.

A further object of the invention is to provide a device of this character which is cheap, durable, and efficient.

The invention consists in the construction, combination, and arrangement of parts hereinafter fully described and claimed.

In the drawings, Figure 1 is an elevation of a portion of a window-frame having supported in front thereof a shade by means of brackets of my improved construction. Fig. 2 is a view in perspective of a shade-bracket constructed in accordance with my invention. Fig. 3 is a similar view thereof, illustrating the position the central portion of the base-plate assumes when the device is in applied position. Fig. 4 is a transverse sectional view of the base-plate, involving a slight modification, the bracket being in side elevation. Fig. 5 is a view similar to Fig. 4, illustrating the position the central portion of the base-plate assumes when in applied position.

1 designates the upper portion of a window-frame having secured thereon brackets 2 of a construction involving my invention and adapted to support in front thereof a shade 3.

4 designates the bracket proper, comprising a supporting-plate 5, having the ends thereof bent upon themselves to provide channels 6 for the reception of the upper and lower edges of a base-plate 7 to adjustably mount the same thereon and to permit of its being secured in its adjustable position. The 50 supporting-plate has secured thereto to project in front thereof a bearing-plate 8, pro-

vided with a suitable bearing 9 for the reception of the gudgeon of a shade-roller.

The base-plate 7 is of an expandible character and is provided with a central flexible 55 concavo-convex portion 10, which when forced into a vertical plane increases the width of the plate by forcing the edges thereof laterally from its longitudinal center and into frictional engagement with the terminal 60 walls of the channels 6, whereby the bracket 4 is secured in its applied position thereon. The portion 10 has projecting therefrom at acute angles flanges 11, adapted to be received by the channels 6 to adjustably mount 65 the bracket 4 upon the base-plate and to permit the edges thereof being forced into frictional engagement with the terminal walls of the channels 6 to lock the bracket in its adjusted position. The flanges 11 by virtue 70 of their acute disposition with relation to the portion 10 permit the mounting of the bracket upon the base-plate to be moved thereon without coming in contact with the window-frame when the device is in applied 75 position, thereby facilitating the free adjustment of the bracket. The portion 10 is provided with perforations 12, through which pass screws 12^a or other fastening means to secure the device in applied position and 80 through the medium of which the plate may be expanded, as illustrated in Figs. 3 and 5, to lock the bracket 4 in its adjusted position.

In Figs. 4 and 5 I have illustrated a slight modification of my invention, which modification lies in interposing between the flanges 11 and the portion 10 horizontally-disposed flanges 13, which support the flanges 11 a sufficient distance from the window-frame to permit the adjustment of the bracket 4 upon 90 the base-plate without liability of contacting with the window-frame.

The operation of the device may be explained as follows: The base-plates may be secured in applied position upon the window-frame through the medium of screws or other fastening means, which application of the devices forces the portions 10 against the window-frame to a vertical plane, as indicated in Figs. 3 and 5, thereby expanding the 95 plates and consequently placing the edges of the flanges 11 into frictional engagement with

the terminal walls of the channels 6. The brackets may be adjusted upon the base-plates to permit the bearings 9 to receive the gudgeons of a shade-roller by slightly tapping the same with a hammer, and in which 5 adjusted position the brackets will remain through the virtue of the frictional engagement of the walls of the channels 6 by the edges of the flanges 11.

10 The further operation of the device may be explained as follows: The brackets may be partially secured to a window-casing by means of screws or other suitable fastening means, which partial securing of the devices does 15 not alter the shape of the portions 10 and permits of the adjustment of the brackets 4 upon the base-plates for and in a manner that is obvious. The brackets 4 may be locked in their adjusted positions by forcing 20 the portions 10 in a vertical plane, as illustrated in Figs. 3 and 5, through the medium of the fastening means in wholly securing the base-plates in applied positions, thereby binding the upper and lower edges of the 25 flanges 11 against the walls of the channels 6.

It is obvious from the above description, taken in connection with the accompanying drawings, that I provide a shade-bracket in 30 which the bracket proper is locked in its adjusted position in a new and novel manner and one that is cheap, durable, and efficient.

Having described my invention, what I claim is—

35 1. A shade-fixture comprising a base-plate having flanges and a flexible portion between the flanges whereby the base-plate may be expanded, and a bracket adjustably mounted upon the flanges and adapted to be held in 40 applied position by the expansion of the base-plate.

2. A shade-fixture, comprising a base-plate having flanges and a concavo-convex flexible portion whereby the base-plate may be expanded, and a bracket adjustably mounted 45 upon the flanges and adapted to be held in applied position by the expansion of the base-plate.

3. A shade-fixture, comprising a base-plate 50 having flanges arranged at an angle with relation thereto, said base-plate also having a

flexible portion whereby the base-plate may be expanded, and a bracket adjustably mounted upon the flanges and adapted to be held in applied position by the expansion of the base-plate. 55

4. A shade-fixture, comprising a bracket provided with a supporting-plate having bent ends forming channels, a base-plate having a flexible portion whereby the base-plate may be expanded, and edges to the base-plate adapted to be forced into frictional engagement with the terminal walls of the channels when the base-plate is expanded. 60

5. A shade-fixture comprising a base-plate 65 having flanges and a flexible portion whereby the base-plate may be expanded to move the flanges laterally from the longitudinal center of the base-plate, and a bracket adjustably mounted upon the flanges and adapted 70 to be held in applied position by the expansion of the base-plate.

6. A shade-fixture comprising a base-plate having flanges arranged at an angle thereon and a flexible portion whereby the flanges may 75 be moved laterally from the longitudinal center of the base-plate, and a bracket adjustably mounted upon the flanges and adapted to be held in applied position by the expansion of the base-plate. 80

7. A shade-fixture comprising a base-plate having flanges and a flexible portion whereby the flanges may be moved laterally from the longitudinal center of the base-plate, a bracket adjustably mounted upon the flanges 85 and adapted to be held in applied position by the expansion of the base-plate, and means for causing the base-plate to expand.

8. A shade-fixture comprising a base-plate having flanges and a flexible portion whereby the base-plate may be expanded, a bracket 90 adjustably mounted upon the flanges and adapted to be held in applied position by the expansion of the base-plate, and means for expanding and securing the base-plate in applied position. 95

In testimony whereof I affix my signature in presence of two witnesses.

GEORGE FRANK PRICE.
